INTERNAL-COMBUSTION ENGINE.

1,308,123.

Specification of Letters Patent.

Patented July 1, 1919.

Application filed July 2, 1917. Serial No. 178,080.

To all whom it may concern:

Be it known that I, GREGORY J. SPOHRER, a citizen of the United States, residing at East Orange, in the county of Essex, State of New Jersey, have invented certain new and useful Improvements in Internal-Combustion Engines; and I do hereby declare the following to be a full, clear, and exact description of the invention, such as will enable others skilled in the art to which it appertains to make and use the same.

This invention relates to four-cycle internal combustion engines of the type in which the inlet and exhaust valves are operated directly by the piston in its reciprocatory movement within the cylinder to open the valves alternately in successive revolutions of the engine shaft, the inlet valve being opened during the suction stroke of the piston and the exhaust valve being opened at the conclusion or near the conclusion of the power stroke. Broadly stated, the object of the invention is to provide a simple form of valve mechanism for controlling the inlet of the combustible fuel to the cylinders of a four-cycle engine and the exit of the products of combustion from the cylinder and to eliminate the objectionable cam shaft, cams and push rods now commonly used to operate the inlet and exhaust valves. More specifically, the invention relates to improvements in the construction of valve gearing for internal combustion engines of the type illustrated and described in an application for patent filed by me on May 22, 1917, and serially numbered 170,202, and the object of the invention is to provide an improved and simplified construction for a valve gearing of the type illustrated and described in that application.

In accordance with the present invention the inlet and exhaust valves of an internal combustion engine are operated alternately in successive revolutions of the engine shaft by a direct connection from the piston to the valves. This connection extends from the piston upwardly through the head of the engine and carries a pivoted cross-head, the ends of which are connected to the stems of the two valves. The distinguishing feature of the invention resides in the arrangement of the spring means for holding the two valves closed except when they are positively opened by the connection from the valves to the piston and also in the arrangement of

the parts whereby the exhaust valve, when positively opened by the connection to the piston, is held open throughout all or practically all of the exhaust stroke of the engine until it is positively closed by the connection to the piston. A single spring is employed for holding the two valves normally closed and this spring is arranged horizontally or at right angles to the axes of the stems of the valves upon which it acts. The tension of this spring is exerted to extend two telescopic members, which constitute one of the members of two toggles to each of which one of the valve stems is connected. During each downward movement of the piston the connection from the piston to the valve gear operates to straighten one of these two toggles against the tension of the spring and the particular one of the two toggles which is selected for operation depends upon the conditions existing in the cylinder at that time. For this purpose the inlet valve is made of considerably greater area than the exhaust valve so that it will be opened when the pressure in the cylinder is very low or when a partial vacuum exists in the cylinder during the inlet stroke; and at the end of the power stroke, when a substantial pressure exists within the cylinder, the inlet valve will be held upon its seat by reason of its greater area and the exhaust valve alone will be operated.

Such a construction as that above outlined is of special value in that it may be so readily adapted for holding the exhaust valve open during the period of time from the opening of the valve at or near the end of the power stroke by the downward movement of the piston to the closing of the valve at or near the conclusion of the exhaust stroke by the upward movement of the piston. For this purpose it is only necessary to so arrange the parts of the toggle to which the stem of the exhaust valve is connected that the opening movement of the exhaust valve carries the toggle across center. The spring for actuating the toggle will then serve to hold the exhaust valve in the open position until that valve is positively closed by the upward movement of the piston resulting in moving the toggle back across center again. The inlet valve, on the other hand, need be held in the open position for only a very brief interval. Instead of having it opened positively by the down-

ward movement of the piston, it may be opened by the suction produced in the cylinder by the downward movement of the piston. Therefore, the toggle to which this 5 inlet valve is connected is not so arranged as to have it move across center when the inlet valve is opened and consequently the tension of the spring is exerted at once to close the inlet valve as soon as that valve 10 is released by the connection to the piston which insures that the valve will be positively opened.

The invention will be better understood by reference to the accompanying drawings 15 in connection with the following description, which set forth the preferred embodiment of the invention. In these drawings, Figure 1 is a central section through the cylinder of an internal combustion engine showing 20 the valve gear in elevation; Fig. 2 is a top view of the parts shown in Fig. 1; and Fig. 3 is a transverse section through the cylinder, the piston, and the end of the connecting rod showing the relative position of the 25 connection from the piston to the valves.

Referring to these drawings, the cylinder 4, piston 5, connecting rod 6 and water jacket 7 are of the usual or any suitable construction. The upper end of the cylinder is closed by a detachable head 8 provided with passages 9 and 10 therethrough controlled by the inlet valve 11 and exhaust valve 12 respectively. The stems 13 and 14 of the inlet and exhaust valves respectively extend up through elongated bearings 30 in the casting 8.

The stems 13 and 14 of the two valves are extended by pivotally connected links 33 and 34 which are slotted intermediate their 40 ends and these slots receive circular ends of a cross-head 15. This cross-head is pivotally connected at its center to the upper end of a rod 16 which extends downwardly through a bearing in the casting 8 and 45 through the top wall of the piston 5, and the lower end of rod 16 is enlarged as shown at 17. This lower end of the rod lies within a tube 18 which is secured to and lies within the piston 5. The position of this tube 18 with respect to the piston 5 is shown 50 in Fig. 3. The tube is placed as near the axis of the piston as it can be conveniently, but is displaced from the plane of oscillation of the connecting rod 6, as indicated 55 by the dot and dash lines in Fig. 3, and also it is displaced laterally from the short shaft 19 connecting the piston 5 and connecting rod 6. At the ends of the tube 18 are buffers 60 of some yielding material such as rubber. The upper end of the tube is closed by a threaded annulus 21.

Between the upper ends of the links 33 and 34 on the stems 13 and 14 of the inlet and exhaust valves is a coiled spring 22 65 whose primary function is to hold the valves

11 and 12 closed until they are positively opened. This spring is horizontally disposed, that is, it lies at right angles to the axes of the valve stems 13 and 14. Its ends bear upon circumferential flanges formed on 70 two telescopic members 23 and 24 which are pivotally connected at their outer ends to the upper ends of the links 33 and 34. A link 25 is pivotally connected at one end to the point of connection of the link 33 and 75 member 23; at its opposite end it is pivotally connected to a standard 26 on the head 8. This link 25 and the members 23 and 24 together form a toggle to the center of which the link 33 on the stem 13 of the inlet valve is connected. A link 27 has one end pivotally connected to the point of connection of the link 34 on the stem 14 of the exhaust valve and the member 24; the other end of this link 27 is pivotally connected to 80 the upper end of a standard 28 on the head 8. This link 27 and the telescopic members 23 and 24 together form a toggle to the center of which the link 34 on the stem 14 is connected. Preferably provision is made for 85 effecting an adjustment of the outer end of the link 27. For this purpose this end of the link may be pivotally connected to a block 29 movable in a guideway formed on the upper end of the stem 28 and held in any 90 selected position of adjustment by screws 30.

Provision may be made, if desired, for assisting the spring 22 in the opening movement of the inlet valve. When the inlet valve is wide open, the toggle, consisting 100 of the link 25 and the members 23 and 24, is moved to a position close to the straight position and therefore the pressure of the spring 22 tending to close the valve is much 105 reduced. The action of the spring at this time may be supplemented by a spring 31 coiled about the valve stem 13 and coacting with a cap 32 mounted on the stem 13. The cap may be so positioned that when the inlet valve 11 is closed, the cap is a substantial 110 distance above the upper end of spring 31. When the inlet valve is opened, the cap is carried into engagement with the upper end of the spring and then compresses the spring. Therefore, when the mechanism 115 for positively opening the inlet valve permits closing of that valve, spring 31 acts with the spring 22 to initiate the closing movement of the valve by pressing upwardly on the cap 32 until the movement of 120 the valve has progressed so far that the cap 32 is carried out of engagement with the end of the spring.

It will be noted that the inlet valve 11 is of considerably greater area than the exhaust valve 12.

The operation of the parts as thus constructed will now be described. Fig. 1 shows the piston at the upper end of its range of movement and the two valves 11 and 12 are 130

closed. Assume now that the piston starts on its downward movement on the inlet stroke. As the piston moves downwardly it establishes a partial vacuum within the cylinder and near the end of the downward stroke the inlet valve 11 is opened. It may be opened by the suction thereon due to the partial vacuum existing within the cylinder and the inlet valve 11 will be so opened 5 while the exhaust valve 12 remains closed because of the substantially greater area of the inlet valve 11. If the inlet valve is not opened by the suction thereon until the piston 5 nears the end of its downward movement, the buffer 20 at the upper end of tube 18 will engage the head 17 of the rod 16 and pull that rod downwardly. The rod will then pull downwardly on the cross-head 15 whose ends engage the two valve stems and 10 one of the stems must yield. This will result in positive opening of the inlet valve 11 as it, rather than the exhaust valve, will yield and be moved downwardly by the cross-head 15. This movement of the inlet valve 11, whether effected by suction thereon or by positive action of the rod 16 on cross-head 15, is accompanied by straightening 15 of the toggle consisting of the link 25 and the members 23 and 24, the members 23 and 24 telescoping more or less against the tension of spring 22. At the end of the downward movement of the piston this toggle will be nearly straight, as indicated by the dotted line on Fig. 1. Therefore, 20 when the piston starts on its upward compression stroke and the buffer 20 at the upper end of tube 18 is carried away from the head 17 of rod 16, the spring 22 will exert its tension to buckle the toggle and thereby raise the inlet valve 11 to the closed position. Additionally, the spring 31 which is compressed during the latter part of the opening movement of the inlet valve, will supplement the spring 22 during the first portion 25 of the closing movement of the inlet valve.

The inlet valve will therefore be closed at the beginning of the compression stroke and both valves will remain closed during the remainder of this stroke. At or near the end of this compression stroke the fuel admitted to the cylinder is ignited and the piston starts downwardly on its power stroke. As it nears the end of its downward stroke the head 17 on rod 16 is again engaged by the buffer at the upper end of tube 18 and rod 16 is again pulled downwardly by the piston. At this time there is a substantial pressure within the cylinder which is exerted upon the two valves 11 and 30 12 and as the valve 11 is of so much greater area than the valve 12, the resistance to opening movement of the exhaust valve 12 will be much less than that of the inlet valve 11. Accordingly, the downward pull of 35 the rod 16 will result in opening of the ex-

haust valve 12, the cross-head 15 rocking on its pivotal connection to the rod 16 in a direction opposite to that in which it rocked when the inlet valve was opened. This opening movement of the exhaust valve will 40 be accompanied by straightening of the toggle consisting of the link 27 and the members 23 and 24, this movement being effected against the tension of spring 22 which is again compressed as before. It will be 45 noted, however, that the pivot of the outer end of link 27 is considerably higher than the pivot of the outer end of link 25, and therefore the same extent of downward movement of the inlet valve will carry the 50 toggle, consisting of link 27 and members 23 and 24, across center, as is indicated by the dotted lines on Fig. 1. Therefore, when the exhaust valve is thus opened, it will remain in the open position until it is positively closed. This valve is opened near the end of the power stroke by the downward pull of the piston on rod 16 and it remains open while the piston moves upwardly 55 on the exhaust stroke. At or near the conclusion of the exhaust stroke the head 17 on rod 16 is engaged by the buffer at the lower end of tube 18 and the rod 16 is positively moved upwardly. At this time the inlet valve which is closed cannot be moved 60 upwardly and therefore the exhaust valve 12 must be. The first portion of this upward movement of the exhaust valve carries the toggle back across center and as soon as it passes the center, spring 22 becomes effective 65 to buckle the toggle to the extent necessary for carrying the exhaust valve 12 to the closed position. This completes the cycle of operations and restores the parts to their initial condition in readiness for a 70 repetition of the inlet stroke.

It will thus be seen that a single spring is made to serve the double purpose of closing both the inlet valve and the exhaust valve and that this is accomplished by arranging the single spring horizontally at right angles to the axes of the stems of the two valves. Furthermore, this spring is arranged to actuate both of the toggles which control the movement of the inlet and exhaust valves and the arrangement of the parts of these toggles is such that the inlet valve is closed immediately on being released by the force which opened it, while the exhaust valve, on the contrary, is held in the 75 open position when it is released by the opening gear until it is positively closed at the proper time. This utilization of a single spring in both of the two toggles for controlling the action of the two valves actuated directly by the piston of the engine, results in a substantial simplification of the mechanism for operating the valves and affords a ready means for holding the exhaust valve open after it has been opened 80

throughout the exhaust stroke of the engine.

I claim:

1. A four-cycle internal combustion engine comprising the combination of a cylinder, a piston, an engine shaft to which the piston is connected, inlet and exhaust valves for the cylinder, a single spring for moving both the inlet and the exhaust valves to their closed positions, and a connection from the piston to the valves including a part reciprocated directly by the piston through which the piston opens the valves alternately during successive revolutions of the engine shaft; substantially as described.

2. A four-cycle internal combustion engine comprising the combination of a cylinder, a piston, an engine shaft to which the piston is connected, inlet and exhaust valves for the cylinder, a single spring arranged at right angles to the stems of said valves for moving the valves to the closed positions and connections from the piston to the valves through which the piston opens the valves alternately during successive revolutions of the engine shaft; substantially as described.

3. A four-cycle internal combustion engine comprising the combination of a cylinder, a piston, an engine shaft to which the piston is connected, a valve, a connection from the piston to the valve whereby the valve is opened by the movement of the piston, and a toggle to which the valve is connected and which is moved across center by the opening movement of the valve to hold the valve open until it is positively closed; substantially as described.

4. A four-cycle internal combustion engine comprising the combination of a cylinder, a piston, an engine shaft to which the piston is connected, an exhaust valve, a connection from the piston to the exhaust valve, a pair of toggle members connected to the exhaust valve, and a spring acting on one of the toggle members; substantially as described.

5. A four-cycle internal combustion engine comprising the combination of a cylinder, a piston, an engine shaft to which the piston is connected, inlet and exhaust valves for the cylinder, toggles to which the valves are connected, spring means for actuating the toggles, and connections from the piston to the valves through which the piston opens the valves alternately during successive revolutions of the engine shaft; substantially as described.

6. A four-cycle internal combustion engine comprising the combination of a cylinder, a piston, an engine shaft to which the piston is connected, inlet and exhaust valves for the cylinder, toggles to which the valves are connected, a single spring actuating both of the toggles and connections

from the piston to the valves through which the piston opens the valves alternately during successive revolutions of the engine shaft; substantially as described.

7. A four-cycle internal combustion engine comprising the combination of a cylinder, an engine shaft, a piston in the cylinder connected to the shaft and moving within the cylinder on suction, compression, power and exhaust strokes successively, inlet and exhaust valves for the cylinder, spring means for moving the valves to the closed position, said means being also arranged to hold the exhaust valve open when it has been moved to the open position, and connections from the piston to the inlet and exhaust valves for operating the inlet valve in each suction stroke and the exhaust valve near the end of each power stroke in the operation of the engine; substantially as described.

8. A four-cycle internal combustion engine comprising the combination of a cylinder, an engine shaft, a piston in the cylinder connected to the shaft and moving within the cylinder on suction, compression, power and exhaust strokes successively, inlet and exhaust valves for the cylinder, a single spring connected to both of the valves for moving them to the closed position and a connection from the piston to the inlet and exhaust valves including a part reciprocated directly by the piston for operating the inlet valve in each suction stroke and the exhaust valve near the end of each power stroke in the operation of the engine; substantially as described.

9. A four-cycle internal combustion engine comprising the combination of a cylinder, an engine shaft, a piston in the cylinder connected to the shaft and moving within the cylinder on suction, compression, power and exhaust strokes successively, inlet and exhaust valves for the cylinder, a single spring arranged at right angles to the axes of said valves and acting on both of the valves to move them to the closed position, and connections from the piston to the inlet and exhaust valves for operating the inlet valve in each suction stroke and the exhaust valve near the end of each power stroke in the operation of the engine; substantially as described.

10. A four-cycle internal combustion engine comprising the combination of a cylinder, a piston, inlet and exhaust valves, a connection from the piston to the valves, two telescopic members connected to the valves, a spring for extending said members and links pivotally connected to the valves, each forming with said telescopic members a toggle actuated by said spring; substantially as described.

11. A four-cycle internal combustion engine comprising the combination of a cylinder

der, a piston, an engine shaft to which the piston is connected, inlet and exhaust valves for the cylinder, a single spring arranged at right angles to the stems of said valves for moving the valves to the closed positions, and a connection to the valves operated by the engine shaft in each rotation thereof for opening the valves alternately during successive revolutions of the engine shaft under 5 the control of the pressure conditions existing within the cylinder, substantially as described.

12. A four-cycle internal combustion engine comprising the combination of a cylinder, a piston, an engine shaft to which the piston is connected, an inlet valve, an exhaust valve, a connection to the valves operated during each rotation of the engine shaft for opening the two valves alternately in 15 successive revolutions of the engine shaft, and a toggle connected to one of the valves and moved across center by the opening movement of the valve to hold the valve open until it is positively closed; substantially as described.

13. A four-cycle internal combustion engine comprising the combination of a cylinder, a piston, an engine shaft to which the piston is connected, inlet and exhaust valves 20 for the cylinder, toggles to which the valves are connected, spring means for actuating the toggles, and a connection to the two valves operated during each rotation of the engine shaft and opening the two valves alternately during successive revolutions of the engine shaft; substantially as described.

14. A four-cycle internal combustion engine comprising the combination of a cylinder, an engine shaft, a piston in the cylinder 25 connected to the shaft and moving within the cylinder on suction, compression, power and exhaust strokes successively, inlet and exhaust valves for the cylinder, spring means for moving the valves to the closed position, said means being also arranged to hold the exhaust valve open when it has been moved to the open position, and a connection to the two valves actuated once during each rotation of the engine shaft for opening 50 the inlet valve in each suction stroke and the

exhaust valve near the end of each power stroke in the operation of the engine; substantially as described.

15. A four-cycle internal combustion engine comprising the combination of a cylinder, an engine shaft, a piston in the cylinder connected to the shaft and moving within the cylinder on suction, compression, power and exhaust strokes successively, inlet and exhaust valves for the cylinder, a single 55 spring connected to both of the valves for moving them to the closed position, and a connection to the inlet and exhaust valves actuated under the control of the pressure conditions existing within the cylinder once 60 during each rotation of the engine shaft and operating the inlet valve in each suction stroke and the exhaust valve near the end of each power stroke in the operation of the engine; substantially as described.

16. A four-cycle internal combustion engine comprising the combination of a cylinder, an engine shaft, a piston in the cylinder connected to the shaft and moving within the cylinder on suction, compression, power 70 and exhaust strokes successively, inlet and exhaust valves for the cylinder, a single spring arranged at right angles to the axes of said valves acting on both of the valves to move them to the closed position, and a connection to the two valves actuated under the control of the pressure conditions existing within the cylinder once 75 during each rotation of the engine shaft for operating the inlet valve in each suction stroke and the exhaust valve near the end of each power 80 stroke in the operation of the engine; substantially as described.

17. A four-cycle internal combustion engine comprising the combination of a cylinder, a piston, inlet and exhaust valves, two telescopic members connected to the valves, a spring for extending said members, links pivotally connected to the valves, each forming with said telescopic members a toggle actuated by said spring, and means for actuating the two valves; substantially as described.

In testimony whereof I affix my signature.
GREGORY J. SPOHRER.
